UNITED STATES PATENT OFFICE.

HERMAN FREDERICK STEMPLE, JR., OF FORT MADISON, IOWA.

MANDREL FOR ABRASIVE AND POLISHING TOOLS.

1,417,584.

Specification of Letters Patent. Patented May 30, 1922.

Application filed January 13, 1921. Serial No. 436,995.

To all whom it may concern:

Be it known that I, HERMAN FREDERICK STEMPLE, Jr., a citizen of the United States, and a resident of Fort Madison, in the county 5 of Lee and State of Iowa, have invented certain new and useful Improvements in Mandrels for Abrasive and Polishing Tools, of which the following is a specification.

My invention relates generally to mandrels for abrading and polishing tools and particularly, although not necessarily, to dental mandrels for grinding and polishing wheels and discs.

A purpose of my invention is the provision 15 of a mandrel which securely holds grinding and polishing wheels and discs against slippage relative to the mandrel and in such manner as to prevent concentration of stress around the edge of the mandrel thus preventing the wheels from cutting out or breaking at the center and thereby materially prolonging the life of the wheels. Furthermore, my invention provides means for yieldingly supporting the wheels, and one which eliminates the employment of face pins.

I will describe one form of mandrel embodying my invention and will then point out the novel features thereof in claims.

In the accompanying drawings:

30 Figure 1 is a view showing one form of mandrel embodying my invention and having applied thereto a conventional form of grinding or polishing wheel.

Figure 2 is a vertical sectional view of a 35 portion of the mandrel and the wheel shown in Figure 1.

Figure 3 is an enlarged detail perspective view of the arbor of the mandrel shown in Figures 1 and 2.

40 Figure 4 is a detailed perspective view of the clamping screw comprised in the mandrel.

Figure 5 is a perspective view of the cushioning sleeve shown in Figures 1 and 2.

45 Figure 6 is a similar view of the cushioning washer shown in Figures 1 and 2.

Similar reference characters refer to similar parts in each of the several views.

Referring specifically to the drawings and 50 particularly to Figures 2 and 3, my invention in its present embodiment comprises an arbor A having its tool carrying end bored, as indicated at 15, and interiorly threaded to receive a clamping screw S. The extreme 55 end of the arbor A is formed with a head 16 of disc formation with its periphery formed

at intervals with recesses 16^a. The clamping screw S comprises a threaded shank 17 which appreciably exceeds in length that of the bore 15 so as to accommodate the grinding wheel, as will be understood. The screw S also includes a head 18 which is slotted to receive a screw driver in the application and removal of the tool to and from the arbor.

Embracing the tool end of the arbor is a 65 cushioning sleeve K preferably formed of rubber and preferably of the form shown in the drawings. This cushioning sleeve K is adapted to be vulcanized onto the arbor A so as to completely house the head 16 but to 70 maintain the entrance end of the bore 15 open for the reception of the clamping screw S. In the applied position of the sleeve K, it will be clear that the head 16 serves to 75 lock the sleeve against rotation on the arbor, it being understood that the recessed portions 16^a of the head receive portions of the sleeve which effects an interlocking of the two elements so that the sleeve will be caused to rotate with the arbor. It is to be understood that the periphery of the head 16 can 80 be roughened in any suitable manner so long as the interlocking action between its periphery and the sleeve is effected.

A washer W preferably formed of rubber 85 is mounted on the shank 17 of the screw S in the manner shown in Figure 2 so as to cushion the screw head 18 with respect to the grinding wheel and to thus prevent injury of the latter by the former.

With a grinding wheel designated at G 90 associated with the mandrel as shown in Figures 1 and 2, it will be clear that the screw S serves to secure the wheel upon the arbor. In this position the wheel is clamped between the screw head 18 and the arbor head 16, but the opposite sides of the wheel actually contact with the cushioning sleeve K and the washer W so that it may be said 95 that the wheel is yieldingly secured upon the mandrel. As the sleeve is vulcanized on the arbor A and locked against relative rotation by means of the head 16, it will be clear that in the applied position of the screw, the wheel is fixedly secured against 100 rotation with respect to the arbor. The diameter of the outer end of the cushioning sleeve K is such as to cover a relatively large area of the corresponding side of the wheel, the actual diameter of the sleeve K 110 exceeding the diameter of the head 16. It is by virtue of this sleeve that concentra-

tion of stresses around the axis of the wheel and the edge of the head 16 is prevented, it being understood that the elasticity of the sleeve K serves to cushion and distribute 5 all stresses imparted to the wheel during the actual use of the latter. The washer W likewise serves a similar purpose while at the same time preventing injury to the disc by the screw head 18. It is by virtue 10 of this distribution of stress as a result of the cushioning sleeve K that the grinding wheels are protected against being cut out at their center which is the main objection to the use of mandrels heretofore constructed. By the elimination of this undue 15 wear at the axis of the grinding wheel, it is obvious that the life of the wheel is materially prolonged and that the possibility of the wheel breaking due to excessive 20 strains at its axis, is eliminated. The cushioning sleeve because of its elasticity also serves to absorb sudden shocks which frequently occur during the grinding operation, and which prevents the transmission 25 of these shocks to the grinding wheel.

Although I have herein shown and described only one form of mandrel embodying my invention, it is to be understood that various changes and modifications may be 30 made herein without departing from the spirit of the invention and the spirit and scope of the appended claims.

What I claim is:

1. A mandrel comprising, in combination, 35 an arbor bored at one of its ends, a head of irregular outline formed on the bored end of the arbor, a cushioning sleeve embracing the bored end of the arbor and said head, a clamping screw threadedly fitted within 40 the bore of the arbor, and a resilient washer mounted on the shank of said screw.

2. A mandrel comprising, an arbor, a metal head formed on one end of the arbor and having radial recesses at intervals in 45 its periphery, and a rubber sleeve encasing the head and having portions thereof disposed in said recesses, the sleeve and the head end of the arbor being axially bored and adapted to receive a member for 50 securing the tool on the mandrel.

3. A mandrel comprising, an arbor, a metal head formed on one end of the arbor and having radial recesses at intervals in 55 its periphery, a rubber sleeve encasing the head and having portions thereof disposed in said recesses, and removable means extending into the sleeve and arbor for removably securing a grinding disc or wheel to the arbor.

4. A mandrel comprising an arbor, a metal head formed on one end of the arbor and having radial recesses at intervals in 60 its periphery, a rubber sleeve encasing the head and having portions thereof disposed in said recesses, the head end of the arbor being bored axially and threaded, and a screw 65 extending into the sleeve and engaging the threaded portion of the arbor for clamping a disc or wheel against the sleeve.

5. A mandrel comprising an arbor, a metallic head of irregular outline formed at one end of the arbor, a resilient sleeve of conical form fixedly secured to the arbor and embracing the head, and means extending 70 through the sleeve and into the arbor 75 for securing a tool to the arbor and against said sleeve.

6. A mandrel comprising an arbor, a metal head formed on one end of the arbor having radially extending recesses formed 80 at intervals in the periphery thereof, a cone-shaped rubber sleeve fixedly secured to the arbor and embracing said head in such manner that portions of the sleeve repose within said recesses, and means extending 85 into the sleeve engaging the arbor for securing a tool against the sleeve.

7. A mandrel comprising an arbor, a metallic head formed on one end of the arbor and having radially extending recesses 90 formed on the periphery thereof, a cone-shaped rubber sleeve vulcanized on the arbor and arranged in such manner that its base projects from one end of the arbor to 95 constitute the face of the tool-end of the arbor, said sleeve embracing said head and having portions thereof disposed in said recesses to effect the interlocking of the sleeve with the arbor, and means extending into the sleeve and engaging the arbor for 100 detachably securing a tool against the base end of the sleeve.

8. A mandrel comprising an arbor, a cone-shaped rubber sleeve embracing the arbor at one end with its base end projecting 105 from the end of the arbor, means for locking the sleeve against movement on the arbor, and means for detachably securing a tool against the projecting end of the sleeve.

9. A mandrel comprising an arbor, a cone-shaped rubber sleeve fixedly secured to one end of the arbor in such manner that the base of the cone projects from one end 110 of the arbor, and a clamping screw threadedly fitted within the arbor for securing a tool against the base-end of the sleeve.

HERMAN FREDERICK STEMPLE, Jr.
